UNITED STATES PATENT OFFICE.

JESSE LA BAR, OF SLATINGTON, PENNSYLVANIA.

FOLDING SLATE.

SPECIFICATION forming part of Letters Patent No. 267,902, dated November 21, 1882.

Application filed February 10, 1882. (Model.)

To all whom it may concern:

Be it known that I, JESSE LA BAR, of Slat-
ington, in the county of Lehigh and State of
Pennsylvania, have invented a new and use-
5 ful Improvement in Folding Slates, of which
the following is a specification and accompa-
nying drawings, in which—

Figure 1 is a perspective view of my im-
proved slate; Fig. 2, a partial perspective
10 view of the open slate; Fig. 3, a partial lon-
gitudinal section of the open slate.

The object of my invention is to fasten
15 hinges to reversible slates, so as to render it
unnecessary to blemish, perforate, or weaken
the frame of the slate by fastening the hinges
to slate-frames, as heretofore, to avoid the noise
and scratching desks in school-rooms while
20 opening and folding the slates, and in case of
removing the hinges at any time to leave the
frame in a perfect and unblemished condition,
having for its advantages the simple mode of
construction, strength, and durability. Other
25 methods that heretofore were used in fastening
hinges to slate-frames are objectionable for the
reason that slate-frames are always weakened
and blemished thereby.

In the drawings, A is the slate; B, the
frame; C, the web-hinges.

Fig. 3 shows the mode of fastening the web
30 C with the slate A in the grooves, thereby
substantially securing the webbing while
framing the slates.

In Fig. 3, D D show a part of the web fast-
ened with the slate reverse to the other, C C.
35 Thereby four pieces of web form two com-

plete hinges, one near each end of the slate,
as shown in Figs. 1 and 2, and thus giving
distinctly the required and aggregate move-
ment to the slate (within the thickness of the
two slates)—three hundred and sixty degrees— 40
in relation with the other.

The construction of my invention is as fol-
lows: When framing the slates, three, four,
or more pieces of web (or any textile material)
may be used, long enough to reach around the 45
frames in and under the slates into the grooves
of the frames b' b', and these are fastened at
each end with the slate by the pressure of
the slate in the groove of the frame, as shown
in the drawings, Figs. 3, C C and D D, thereby 50
making a complete hinge to the slate, and
giving the required articulation to the slates.

Having thus described my invention, what I
claim as new, and desire to secure by Letters
Patent, is—

1. The combination of two slate-frames,
slates inserted therein, and flexible hinges,
these hinges having their ends secured rigidly
in their places in the groove formed in the
frame by the edges of the slates, all substan- 60
tially as and for the purposes set forth.

2. As a new article of manufacture, a fold-
ing slate consisting of two single slates and
flexible connecting-pieces secured into the
slate-frames by means of the slates themselves, 65
substantially in the manner described.

JESSE LA BAR.
